SORTING AND BINDING DESK

Filed Dec. 21, 1925

UNITED STATES PATENT OFFICE.

EMIL K. OHM, OF ATHENS, OHIO; ROBERT J. STUDER, ADMINISTRATOR OF EMIL K. OHM,
DECEASED.

SORTING AND BINDING DESK.

Application filed December 21, 1925. Serial No. 76,611.

This invention relates to sorting and binding desks and is designed for the manipulation, sorting and binding of papers which are to be perforated and bound for filing and other purposes.

With the above and other objects in view, as will be apparent, this invention consists in the construction, combination and arrangement of parts, all as hereinafter more fully described, claimed and illustrated in the accompanying drawing wherein:

Figure 1 is a perspective view of a desk constructed in accordance with the present invention;

Figure 2 is a plan view of the binding compartment illustrating the door thereof closed and the top pressure plate in position;

Figure 3 is a similar view with the top pressure plate removed and door open disclosing the bottom of the binding compartment;

Figure 4 is a transverse section taken along line IV—IV of Figure 2 to illustrate the mounting of the top pressure plate and its cooperation with the perforation guide;

Figure 5 is a section taken at right angles to Figure 4 along line V—V of Figure 2;

Figure 6 is a vertical section taken along line VI—VI of Figure 4 and showing the construction and mounting of one of the bushings which may be used in conjunction with the perforation guide; and

Figure 7 is a plan view similar to Figure 3 illustrating a modified form of the present invention wherein the perforation guide is carried by the door of the binding compartment.

Where there are large numbers of papers to be filed it is customary to sort them according to a predetermined classification and to then bind the various classes thus obtained, permanently or otherwise, into bundles. Economy of space requires that the papers making up the respective bundles be compressed to the fullest extent possible and as the papers are not customarily perforated for binding it is necessary that the perforations for the reception of the binding elements be placed therein. The present invention is designed to provide a desk upon which this sorting may be done, which will have a compartment for the reception of the various groups of papers after sorting, for the compression thereof, said compartment be-

ing provided with means for maintaining the papers of the group in the compartment in a compressed condition. While the papers are thus being held they may be perforated at convenient points determined by a perforation guide in conjunction with the compartment and bound together by standard fastening means such as laces, binding posts, pins and the like.

In carrying out the present invention, a desk 10 is provided having a wide, flat sorting surface 11, surrounding a binding compartment 12 inset therein adjoining the forward edge thereof. This compartment 12 is of a size sufficient to receive in a flat or horizontal position the largest sheet it is desired to bind and of a depth sufficient to entirely contain the largest bundle of papers it is desired to create.

The bottom 13 of the compartment 12 is flat and occupies a plane parallel to the plane of the sorting surface 11 of the desk 10. Along its forward edge the bottom 13 has a slot 14 which, as will be hereinafter more fully described, permits of the binding or fastening of the bundle while it is still in the compartment 12.

At its side, corresponding to the front edge of the sorting surface 11, the compartment 12 is open and is there provided with a gate 15 adapted to swing on the hinges 16 between one end of the gate and the front end of one of the side walls 19 of the compartment. The free ends of the gate 15 has a latch or bolt or other fastening means 17 mounted thereon for cooperation with a sleeve or other engaging means 18 at or adjoining the forward end of the remaining side wall 19 of the compartment 12 to lock the said gate in a closed position. (Fig. 95)

The side walls 19 of the compartment 12 are each provided with a series of grooves 20 for the reception of the top pressure plate 21. The opposed grooves 20 of the side walls 19 are coplanar so that the top pressure plate 21 when inserted in a pair thereof, occupies a position substantially parallel to the bottom 13 of the compartment 12. As the grooves 20 extend to and through the front ends of the side walls 19 of the compartment 12, the top pressure plate 21 may be inserted in any two opposed coplanar grooves, when the gate 15 is open.

After the papers have been sorted or classi-

fied on the sorting surface 11, each pile, group or class is placed in the binding compartment 12 with the edges to be bound at the front thereof. When the gate 15 is closed the edges to be bound of the papers are placed or bear against the gate, which acts as a guide and abutment therefor. If the papers are of less dimensions than those of the compartment 12, one of the sides at right angles to the edges to be bound may be placed against the adjoining one of the side walls 19 of the compartment 12 which likewise acts as a guide or abutment therefor. Thus after the gate 15 is closed, the papers placed in the compartment 12 are positioned by the gate 15 and walls 14 so that at least two of the edges of each sheet rest in the same, or approximately the same, vertical plane as the corresponding edges of the remaining sheets contained in the compartment. A pile or group of sheets or papers of less dimensions than those of the compartment 12 are indicated at 22 (Figures 2, 4 and 5). In the event the papers or sheets are of the same dimensions as the compartment 12, the edges thereof bear against both side walls 19, the gate 15 as well as the rear wall of the compartment, but in every case the edges to be bound should bear against the gate 15.

Subsequent to arranging the sheets and papers as aforesaid, they are compressed as much as possible and held in this condition until the gate 15 is opened and the top pressure plate 21 inserted in the grooves 20 that will most nearly position the plate 21 tightly against the top of the pile, such as 22, as shown. In this manner the stack of sheets 22 in the compartment 12 are held compressed by the plate 21 for perforating and binding.

In the binding stack or pile of sheets not already punched, such as that shown at 22, it is necessary to perforate the sheets at predetermined intervals adjoining the edges to be bound, for the reception of the binding or fastening means such as laces, pins or the like. The perforations have in past been formed in the papers by means of an electric drill and it is the purpose of the present invention to cooperate with such drill by providing a guide for the same and to determine the location of the perforations whereby the holes created will be straight and properly positioned.

For this purpose the top pressure plate 21 is provided with a slot 23 adjoining the outer edge thereof, which when the pressure plate is positioned in the grooves 20 so that the rear end thereof is at the terminals of the groove, said slot 23 will be aligned vertically with the slot 14 in the bottom 13 of the compartment 12. This slot at predetermined intervals merges into enlargements 24 which correspond to the shape but are somewhat larger than the drill used to perforate the stack or pile of sheets 22. These enlargements 24 cor-

respond to similar enlargements 25 formed in the slot 14 of the bottom 13 of the compartment 12 so that the drill will in its operation through the sheets pass through both the enlargements 24 and 25.

Cooperating with the pressure plate 21 is a guide 26 which constitutes a block cooperating with the plate and having a slot 27 registering and co-extensive with the slot 23 of the plate 21. This slot 27 of the guide 26 is provided with a series of enlargements 28 which are so spaced that they register with the similar enlargements 24 of the plate 21. These enlargements 28 however are of a greater diameter than the diameter of the drill used for the reception of the guiding bushings 29 which are inserted therein and each of which has a passage 30 therethrough, of a diameter substantially equal to the diameter of the drill used. These bushings are removable from the guide 26 and may be and are inserted in the enlargements 28 through which the drill is to be passed during the perforation of the papers.

In practice, after the papers have been clamped as illustrated at 22 in Figures 2, 4 and 5, the electric drill is inserted into the passages 30 of the bushings situated adjoining and over the bundle of paper thereby drilling a hole through the papers under the plate 21. By the use of the bushings 29 the drill is braced and guided so that it will not budge or bend in passing through the papers and will drill a straight aperture therethrough, and by having the enlargements 25 in the slot 14 the drill after passing through the sheets will enter the same rather than impinging on the bottom 13 to be broken thereby.

When the papers have been punched before being received for arranging and binding, the perforating operations referred to hereinbefore are not necessary but the papers are arranged in the compartment 12 in the same manner as if for perforation.

After the papers have been arranged and the operations performed as aforesaid, and while the papers are held compressed by the plate 21, the fastening means such as laces, pins or the like are inserted therein, the slots 14 and 23 and the enlargements 25 and 24 thereof are sufficiently large to permit fastening means to pass therethrough and engage and secure the papers. When this is done the plate 21 is removed and the bundle is ready to be filed.

In the form of the invention shown in Figure 7, the guide 26^a having the slot 27^a and the enlargements 28 is carried by the gate 17 so that after the pressure plate 21 which in this instance does not carry a guide 26 is in place, the gate may be closed and the guide 26^a may be used during creation of the perforations in the paper.

It will be observed from Figure 4 that one

side of each groove 20 is shown positioned at an angle to the opposite side thereof. While the grooves may have parallel sides, it is possible by the arrangement shown, to use a pressure plate of spring material whereby the same may be forced downwardly and spring from one groove 20 to the other. This makes it possible to compress the sheets simultaneously with the insertion of the top pressure plate 21.

What is claimed is:

1. In a binding machine for paper or other sheets, a receiver having a bottom and side walls, the said bottom having a slot formed therein adjacent its front edge, the said side walls having grooves formed therein and extending along a portion thereof to an abutment, and a pressure plate having a slot therein adjacent one edge thereof, the said plate arranged to be received by the said grooves and to engage the said abutment so that its slot will register with that in the bottom of the receiver.
2. A binding machine for paper or other sheets, comprising a compartment open at the top and front and having a bottom in which a slot is formed adjacent the front edge thereof, a pressure plate in the com-

partment parallel to the bottom thereof and having a slot formed therein adjacent its front edge and registering with the slot in the bottom of the compartment, and a drill guiding member positioned above the pressure plate having a slot formed therein registering with the slot in the pressure plate, and removable bushings engaging within the slot in the said guiding member.

3. A binding machine for paper or other sheets, comprising a compartment open at the top and front and having a bottom in which a slot is formed adjacent the front edge thereof, a pressure plate in the compartment and having a slot formed therein adjacent its front edge registering with the slot in the bottom of the compartment, a gate hinged at one end for closing the front of the compartment adapted to align sheets within the compartment, a perforating guide swingable with said gate, and drill guiding bushings removably inserted in the said perforating guide registering with the slot in the pressure plate.

In testimony whereof I have hereunto subscribed my name.

EMIL K. OHM.
